ATTORNEYS

UNITED STATES PATENT OFFICE.

GEORGE J. PFAHL, OF WHITE PLAINS, NEW YORK.

COLUMN.

SPECIFICATION forming part of Letters Patent No. 644,777, dated March 6, 1900.

Application filed September 15, 1899. Serial No. 730,548. (No model.)

To all whom it may concern:

Be it known that I, GEORGE J. PFAHL, a citizen of the United States, residing at White Plains, in the county of Westchester and State 5 of New York, have invented certain new and useful Improvements in Columns, of which the following is a full and complete specification, such as will enable those skilled in the art to which it appertains to make and use 10 the same.

This invention relates to columns; and the object thereof is to provide an improved column which is built up of several sections which are connected and bound together in a 15 completed column by improved means according to my invention.

The invention is fully disclosed in the following specification, of which the accompanying drawings form a part, in which the separate parts of my improvement are designated by the same numerals of reference in each of the views, and in which—

Figure 1 is an end view of a column constructed according to my invention; Fig. 2, 25 a perspective view of one of the sections thereof, and Fig. 3 a perspective view of a tie-block which I employ to bind the members of the column together.

In the drawings forming part of this specification I have shown at 5 one of the sections of a column, and, as shown in the drawings, the column is constructed of twelve of said sections, which are preferably convoluted upon their adjacent sides. The section 5 comprises two forms, one of which is shown at 5^a and the other at 5^b, each of which consists of a strip or block of wood or other suitable material. The sections shown at 5^a have their sides convoluted by means of two longitudinal grooves 6 and 7, which are separated by a longitudinal rib 8. The grooves 6 are preferably deeper than the grooves 7, and said grooves and the intermediate rib 8 form a continuous curve terminating in plane portion 11 and 12 upon the sides of the section 5^a. Each of the sections 5^b is provided with convoluted sides which are exactly the reverse in their groove and rib formations to the sections 5^a, and when placed together an 45 edge of one of the sections 5^a will fit accurately into an edge of a section 5^b.

Each of the sections 5^a and 5^b is formed

with an inner face 9, which is preferably plain and smooth, and the faces 9 are narrower than the outer faces 10, whereby when the sections 5^a and 5^b are connected in a continuous series by fitting the edges thereof together, as above described, a polygonal column is formed. The outer surface of the column is then preferably turned or otherwise 60 cut down to form a true cylinder, which may be fluted or otherwise decorated as desired.

In forming the complete column, as shown in Fig. 1, I connect a number of the sections 5^a and 5^b, sufficient to form, preferably, one-half of a column, the several sections thereof being glued or otherwise made to adhere, as may be desired, and allow the completed half-column to dry and set. When two column halves or members have been completed, as 70 above-described, I place them together to form a completed column, gluing or otherwise securing the adjacent ends of the two halves in the same manner as the separate sections of each half are secured together. I then connect the two column members or halves together internally by means of tie-blocks 13, 75 which connect the adjacent sections at the ends of the column halves or members.

The tie-blocks 13 are of the form shown in Fig. 3 and provided upon their inner faces with dovetail tongues 14 and angular ribs 15. The tongues 14 take into similar grooves 16, formed in the members 5^a and 5^b, as shown in Fig. 2, and the ribs 15 closely fit the angularly- 85 diverging inner faces of the adjacent sections 5^a and 5^b, with which said tie-blocks 13 are connected.

In securing the tie-blocks 13 in operative position they are preferably inserted at the 90 top and bottom of the column, as many being used as desired, and are driven home in any desired manner, the tongues 14 binding the blocks 13 closely to the sections 5^a and 5^b and also closely binding the column members or 95 halves together.

If the column be initially formed of a plurality of sections glued together or otherwise caused to adhere, there is great danger of disintegration of the column. Furthermore, 100 when the complete column is formed as an entirety and then allowed to set and dry the result is variable and not as satisfactory as when the column is built up of two halves or

members each of which is separately formed and both of which are connected firmly, as according to my improvement.

It is evident that I may slightly vary the 5 construction and arrangement of the elements described as embodying my invention without departing from the spirit or sacrificing the advantages thereof.

Having fully described my invention, I 10 claim as new and desire to secure by Letters Patent—

1. A column consisting of a plurality of longitudinal sections which fit each other at their edges and are provided upon their inner surfaces with dovetail grooves, the inner sides of said sections diverging angularly, and angular tie-blocks which fit said inner surfaces of said sections and are provided with dovetail tongues which take into said grooves 15 20 therein, substantially as shown and described.

2. A column composed of separate longitudinal sections, two of which are fitted at their edges by longitudinal grooves and ribs, the inner surfaces of said sections diverging angularly, dovetail grooves formed in the inner 2 surfaces of said sections, and an angular tie-block which fits the inner surface of said sections at their line of connection and is provided with dovetail tongues which fit said dovetail grooves in said sections, substantially as described.

In testimony that I claim the foregoing as my invention I have signed my name, in presence of the subscribing witnesses, this 14th day of September, 1899.

GEORGE J. PFAHL.
